UNITED STATES PATENT OFFICE.

SOLOMON B. ELLITHORP, OF ROCHESTER, NEW YORK.

LASTING-MACHINE.

SPECIFICATION forming part of Letters Patent No. 247,625, dated September 27, 1881.

Application filed August 8, 1881. (No model.)

To all whom it may concern:

Be it known that I, SOLOMON B. ELLITHORP, of Rochester, in the county of Monroe and State of New York, have invented a new and 5 Improved Boot and Shoe Lasting Machine, of which the following is a specification.

This invention is designed as an improvement on the lasting machine for which Letters Patent No. 236,218 were granted to me January 4, 1881; and it consists in making the last-seat, toe-rest, clamp-suspending hooks, pressing-bolts, levers, and certain other operating parts adjustable, whereby the machine is more readily adapted to shoes and boots of various 15 sizes, all of which will be hereinafter described.

In the accompanying drawings, Figure 1 is a partly-sectional side elevation of the machine with parts broken away to exhibit other parts. Fig. 2 is a sectional elevation of the same on line $\alpha\alpha$, Fig. 1. Fig. 3 is a plan of the same with parts broken away to exhibit other parts.

Similar letters of reference indicate corresponding parts.

In the drawings, A represents the frame of the machine, and B a longitudinally-slotted bar extending centrally across its bottom and forming part thereof. The standard C' of the seat C for the heel of the last D is adjustably held in place so as to be moved along the bar 25 B by its spindle a', which projects through the slot b in the bar B, and has a nut, c, on its end. This seat C has a downward-projecting spindle, a, that is adjustably held in a corresponding socket, a', in the standard C' by a set-screw, a'; hence it will be seen that the said seat C may 30 be adjusted longitudinally and vertically by means of the nut c and set-screw a'. The standard E' of the seat E for the toe of the last D is also held in the bar B so as to be longitudinally adjustable by its spindle d and nut d'; and said seat E has a concave face, so as to fit 35 about the toe of the last D, as shown in Fig. 1, and has a downward-projecting spindle, d', that is held in a corresponding socket, d', in the standard E', by a set-screw, d'; and said seat E is preferably covered with leather or other soft material, as indicated at d', to prevent injury to the shoe-upper D', that is shown on the last D. The seats C E may be approached 40 to or separated from each other to adapt them to lasts of different sizes, and may be verti-

cally adjusted for the same purpose. A standard, F, is also held in the slot of the bar B by spindle f and nut f', and in the socket f' of this standard F is adjustably held by set-screw f' a 55 fork-headed spindle, F', in the head of which a lug, F', is held on a horizontal pin, f'. On vertical pins g g, that are held in the inward-projecting end of this lug F', are pivoted the levers G, so as to move in horizontal planes. 60 These levers G consist of metallic bars inwardly curved to conform with the side outlines of the last D, near the bottom thereof, and they are also curved flatwise to conform in a measure with the curve of the bottom of 65 the last D. These levers G are of sufficient length for their rear ends, which are prolonged into handles, to rest on a vertically-adjustable cross-bar, G', of the frame A, as shown, whereby they may be held at any desired vertical 70 inclination, and are so hinged on the pins g g that they can be closed about the last D and leather D', and can be opened apart to permit the easy removal of last D and leather D' that is stretched upon it. A clamp, g', slipped over 75 the ends of the levers G, holds them together about the last and leather D D'.

H is a flat metal plate, called a "templet," of the general shape of the bottom of the last D, and provided with holes h h around its edge 80 for the reception of the screw-hooks H', that suspend the clamps I, which hooks H' and clamps I are vertically adjustable by means of nuts h' on the ends of the former, as shown, whereby more or less tension can be applied 85 at any point of the leather D'. Said templet H is longitudinally slotted, and is provided on its upper surface with lugs m m, by means of which it is suspended on pins m' m' from rods K, which extend up through the slotted cross-bar A' in the top of the frame A, and have their upper ends pivoted to levers L, that are, in turn, pivoted or fulcrumed on pins n in the tops of the standards M, which are adjustably held by their spindles n' and nuts n' on the 90 slotted bar A'. To the long arms of these levers L are pivoted rods L', that have their lower ends slotted, as shown at o, and are extended down through the longitudinal slot p of the bar A'. 100

A shaft, O, journaled in hangers O', extends longitudinally through the frame A a little be-

low and at one side of the bar A^2 , and on this shaft O are loosely fixed two arms or cranks, O^2 , whose ends are held in the slots o of the rods L' by pins q . This shaft O is provided 5 with a hand-wheel, P , by turning which the levers L are moved through the rods $K L'$ to elevate or depress the templet H , and thereby adjust the tension of the hooks and clamps $H' I$. The clamps I are suspended from the hooks 10 H' with their clamping-points downward to seize the edges of the leather D' , and they are provided with eccentric levers m^2 for adjusting the gripe of their jaws or points upon the said leather D' . On loosening the nuts n^2 the 15 templet H , levers L , cranks O^2 , and their connecting-bars can be moved parallel with the bar A^2 for the adjustment of the said templet H over the last D .

Q represents the holding or pressing screw- 20 bolt, provided with hand-wheel Q' , that passes down through plate r , bar A^2 , and guide-plate s , and freely through the templet H , with its points resting on the last D , for the purpose of holding the latter firmly down in its seat 25 during the process of lasting a boot or shoe, and said bolt Q may be screwed up or down in the plates $r s$, that are made to grasp the bar A^2 between them by the thumb-screws s' ; and by loosening said screws s' said bolt Q 30 may be moved laterally, that its pressure may be applied to any part of the bottom of the last D that may be desired.

In the drawings two sheaves, g' , are shown journaled in a socket in the cross-bar G' , which 35 sheaves are for a cord to run over when the machine is operated by power, in which case the cord will be made fast to a slide that may be moved to and fro to open and close the curved levers G .

40 Having thus fully described my invention, I claim as new and desire to secure by Letters Patent—

1. In a lasting-machine constructed substantially as herein shown and described, the combination of adjustable heel-seat and standard 45 $C C'$, adjustable toe-seat and standard $E E'$, adjustable clamping-lever standard F , adjustable templet H , adjustable hooks and clamps $H' I$, adjustable levers L , with their attachments, and adjustable pressing screw-bolt Q , 50 arranged as set forth.

2. The combination, with the toe-seat E , standard E' , and bar B , of the spindles $d d'$, nut d' , socket d^3 , and screw d^4 , as and for the purpose described.

3. The combination, with the levers G , of a socketted standard, F , slotted bar B' , spindle and nut $f f'$, screw f^3 , the spindle F^2 , having lug F^3 , and the pins $f^4 g$, as and for the purpose described.

4. In a lasting-machine, the hooks H' , threaded at one end and provided with nuts h' , in combination with the templet H , as and for the purpose set forth.

5. In a lasting-machine, as a means for longitudinally and vertically adjusting the templet H and hooks and clamps $H' I$, the combination, with the slotted bar A^2 , of the rods K , levers L , adjustable standards M , rods L' , cranks O^2 , shaft O , and their respective pivots 70 and nuts, substantially as herein shown and described.

6. In a lasting-machine, the combination, with the bolt Q , of the plate r , bar A^2 , guide-plate s , templet H , and screws s' , as and for 75 the purpose specified.

The above specification of my improvement in boot and shoe lasting machines signed by me this 19th day of July, 1881.

SOLOMON B. ELLITHORP.
